(57) **CLAIM**

The ornamental design for a microscope, as shown and described.

DESCRIPTION

FIG. 1 is a front, perspective view of a microscope according to my novel design;

FIG. 2 is a right side view of the microscope according to my novel design;

FIG. 3 is a left side view of the microscope according to my novel design;

FIG. 4 is rear view of the microscope according to my novel design;

FIG. 5 is a front view of the microscope according to my novel design;

FIG. 6 is a top view of the microscope according to my novel design; and,

FIG. 7 is a bottom view of the microscope according to my novel design.

1 Claim, 4 Drawing Sheets

FIG. 1

FIG. 3

FIG. 2

FIG. 5

FIG. 4

FIG. 7

FIG. 6

UNITED STATES PATENT AND TRADEMARK OFFICE
CERTIFICATE OF CORRECTION

PATENT NO. : Des. 460,096 S
DATED : July 9, 2002
INVENTOR(S) : Christophe Apothéloz

Page 1 of 1

It is certified that error appears in the above-identified patent and that said Letters Patent is hereby corrected as shown below:

Title page.

Item [73], Assignee, replace "Wetzlar (DE)", with -- Heerbrugg (CH) --.

Signed and Sealed this

Twenty-eighth Day of March, 2006

A handwritten signature in black ink, appearing to read "Jon W. Dudas". The signature is written in a cursive style with a large, stylized 'J' and 'W'.

JON W. DUDAS
Director of the United States Patent and Trademark Office
